UNITED STATES PATENT OFFICE

2,512,436

SHOE MACHINE

Alfred R. Morrill, deceased, late of Woodstock, Vt., by Ruth W. Morrill, administratrix, Woodstock, Vt., assignor to United Shoe Machinery Corporation, Flemington, N. J., a corporation of New Jersey

Application May 27, 1947, Serial No. 750,705

12 Claims. (Cl. 112—252)

1

The present invention relates to improvements in shoe machines, and more particularly to an improved means for controlling and for severing the thread upon the completion of a sewing operation about the shoe.

The invention is herein disclosed in a preferred form as embodied in an automatic machine for sewing together the insole, welt and upper of a welt shoe, and for trimming the sewn seam. The machine herein illustrated is similar except as hereinafter pointed out, to that illustrated and described in the copending application of Morrill, pending in the United States Patent Office, Serial No. 669,830, filed May 18, 1946 for Shoe Machines.

The several cooperating instrumentalities of the machine include a channel guide and welt guide for positioning and guiding the shoe being operated upon, an inseam shoe sewing mechanism, and a rotary tubular knife of large diameter which is located adjacent to the sewing mechanism in position to trim the last completed stitch of the seam, and an automatic shoe support consisting of a shoe supporting jack and supporting and actuating connections for moving the jack to cause the shoe to be presented to the operating means and to transfer the operation about the shoe, and automatically acting mechanism for effecting and for controlling the relative movements of the jack and shoe supported thereon and the operating means.

It is a principal object of the invention to provide for use in a machine of the class described having sewing mechanism which includes a hook needle, a looper, a thread finger movable substantially in the line of feed, and a channel guide for guiding the work, a novel and improved thread severing device which is well adapted to cooperate with the elements of the sewing mechanism to control and to sever a portion of the thread leading from the work.

It is a further object of the invention to provide in a machine of the class described having an inseam trimming knife adapted for trimming a portion of the inseam held together by the last completed stitches of the seam, a device for controlling and for severing the thread which includes means operable to cause the thread to be severed upon completion of the last stitch and prior to a further relative movement of the shoe operating devices and shoe to finish-trim the end portion of the inseam.

With these and other objects in view as may hereinafter appear, a feature of the invention consists in the arrangement of the channel guide

2

with a supporting surface formed thereon arranged to be engaged by a portion of the thread extending from the work, and a thread cutter which is movable in cooperative relation to the channel guide to sever a portion of the thread engaged against said surface.

The several features of the invention consist also in the devices, combinations and arrangement of parts hereinafter described and claimed, which together with the advantages to be obtained thereby will be readily understood by one skilled in the art from the following description taken in connection with the accompanying drawings, in which:

15 Fig. 1 is a view in left side elevation of an automatic machine for sewing together the insole, upper and welt of a welt shoe, and for trimming the sewn inseam;

Fig. 2 is an enlarged detail view with a portion 20 of the casing broken away and sectioned and with the inseam trimming cutter and its supporting structure removed to illustrate portions of the driving and stopping mechanism of the machine, portions of the sewing and thread handling mechanism including the inseam trimming knife, and the connections from the driving and stopping mechanism for actuating the knife;

Fig. 3 is an enlarged detail view of the parts of 25 the sewing head shown in Fig. 2, but with the thread severing knife in its advanced thread severing position;

Fig. 4 is a view in front elevation of substantially the parts shown in Fig. 3; and

Fig. 5 is a sectional plan view taken on the line 30 V—V of Fig. 4.

The automatic shoe machine illustrated in the drawings as embodying in a preferred form the several features of the invention, comprises generally the column-shaped support or casing which is made up of several sections including a floor section 10 housing principally the oil sump and various foot treadle controls of the machine, a middle section 12 housing principally the jack supporting mechanism and pattern mechanism 40 of the machine, a head section 14 housing therein the welt sewing mechanism and inseam trimming mechanism together with parts of the driving and stopping mechanism of the machine, and a top section 16 supporting therein the driving motor 18 and reduction driving gears therefrom connecting with the driving and stopping mechanism.

In the illustrated machine, the shoe supported on a last is carried on a shoe supporting jack 55 which for simplicity of illustration is indicated

only by dot-and-dash lines 20 in Fig. 1. The jack may be of any well known construction as that shown, for example, in the patent to Cross No. 2,056,714, dated October 6, 1935. The jack is mounted on a spindle 22 which extends downwardly through and is supported from a jack rotating wheel 24 for swinging movements in any direction. The wheel 24 is in turn mounted on a horizontally extending arm 26 forming part of a lever supporting assembly for the jack not specifically illustrated or described, inasmuch as the details of this mechanism form no part of the invention, and are fully set forth in the Morrill application above referred to.

The driving and stopping mechanism for the machine as best shown in Figs. 1 and 2 of the drawings, comprises the electric motor 18, the armature of which carries a gear 30 (see Fig. 2) which meshes with a gear 32 carried on a sleeve element 34 together with a second gear 36 so that the two gears turn as a unit. A planetary transmission mounted in a housing 38, and a one revolution eccentric mechanism including an eccentric strap 40 carried on an eccentric and eccentric supporting shaft not specifically shown, are mounted directly beneath and are adapted to be driven from the sleeve element 34. The gear 36 meshes with a gear 44 formed integrally with a driving element 46 of the main clutch which is of the cone type and includes a vertically shiftable driven clutch member 48. The driven clutch member 48 is arranged to act through a downwardly extending drive shaft 50, clutch 52, shaft 54 and the reduction gearing generally indicated in Fig. 2, to drive a pattern cam shaft which acts to impart the desired turning, tipping and feeding movements to the jack.

The driven clutch member 48 acts through a driving gear 64 formed integrally therewith, and a cooperating gear 66 to drive the transversely extending sewing cam shaft 68 of the machine.

At the end of an operation about the sole margin of the shoe, an automatic stop mechanism is rendered operative which is similar to and operates in a similar manner to that fully described and illustrated in the copending application of Morrill above referred to. The operations performed include disengagement of the main driving clutch for the machine which disconnects the sewing and pattern cam shafts, a reverse drive of the sewing cam shaft to a predetermined stop position in which the needle is withdrawn from the work, and the rotation of a machine eccentric through one revolution for the performance of a number of auxiliary operations incidental to the stopping of the machine. These operations may include the further advance of the jack and shoe supported thereon for causing the inseam trimming knife to trim a portion of the inseam, the severing of the welt and thread from the work, the movement of the jack and shoe supported thereon away from the operating mechanism, and finally the return of the jack to an initial loading position preparatory for the removal of the finished shoe from the jack. In accordance with the invention, novel means for controlling and for severing the thread are provided which are well adapted for use in combination with the elements of a sewing mechanism of the type described, and more specifically in an automatic machine having an inseam trimming cutter, an automatic shoe support, and the stop devices here set forth. The automatic stop mechanism above referred to, is generally described and illustrated in the copending application of

Morrill above referred to, and will be described herein only so far as is believed necessary to indicate the connection of the present invention therewith.

The stop motion of the machine is thrown into operation by means of a trip mechanism actuated from the pattern cam shaft which permits a laterally extending clutch control shaft 74 (see Figs. 1 and 2) to rock in a clockwise direction to the position shown in Fig. 2, in order to raise clutch operating levers 76 to release the main clutch 46, 48 through which both the pattern cam shaft and sewing cam shaft 68 are driven. The rocking movement of the control shaft 74 acts also to throw into operation an auxiliary stop motion for the sewing cam shaft 68 by effecting an upward movement of a locking bolt 80 with respect to its carrier 82 to connect the carrier with a reciprocating actuating lever 84. The lock bolt carrier 82 is subsequently moved first to an extreme position to the right, and is then returned leftwardly to the stop position shown in Fig. 1.

The movement of the lock bolt carrier 82 to the right and then to the left is employed to set in motion the auxiliary eccentric mechanism above referred to, which provides power for the performance of certain auxiliary operations performed at the completion of the operation about the shoe. As shown in Figs. 1 and 2, a link 88 is connected at one end to the lock bolt carrier 82 and at its other end to a bell-crank 90 which is in turn connected with a vertically extending link 92 supported at its lower end for vertical movement between two guides formed on a control lever arm 94. The link 92 is provided with a notch arranged for engagement with the detent 96 on an eccentric clutch control lever 98. The initial movement of the lock bolt carrier to the right has the effect of raising the control rod 92 to engage the notch therein with the detent 96, and the subsequent leftward movement of the lock bolt carrier then acts to depress the rod 92 so that the lever 98 is rocked to engage the eccentric clutch. The eccentric actuated rock shaft 100 is caused to be rotated first in one and then in the other direction, the return movement of the rock shaft 100 at the completion of one revolution of the eccentric having the effect of moving the lever 94 leftwardly to disengage the notch in the control lever 29 from the detent 96 to disengage the eccentric clutch.

The operating devices of the machine include a chainstitch shoe sewing mechanism having an oscillatory curved hook needle 120 supported for feeding and return movement in the line of feed, an oscillatory looper 122 and a thread finger 124 which is movable in a direction substantially parallel to the line of feed and away from the trimming knife, these parts being located entirely at that side of the sewing point away from the completed stitches of the seam to cooperate with a rotary tubular knife 130 which is of relatively large size with its axis parallel to the line of feed and with the cutting edge of the knife passing transversely across the sewn inseam.

The inseam trimming mechanism which forms one of the operating devices of the machine, as best shown in Figs. 3 and 4, comprises the trimming knife 130 having a tapered periphery which rotates in close proximity to the point of operation of the sewing devices including the curved hook needle 120 and channel guide 138 of the machine. The cutting edge of the knife 130 is adjustable in the line of feed and is spaced from the sewing devices including the curved hook

needle 120 and channel guide 138 in the direction of the completed stitches of the seam by an amount which is sufficient only to cause the trimming knife to trim that portion of the sewing rib held together by the last completed or tightened stitch of the inseam. Under normal operating conditions the position of the knife will be adjusted so that its cutting edge will be approximately one-half inch to the left of the point of pivotal support of the shoe as determined by the engagement of the channel guide therewith. The trimming knife operates simultaneously with and in conjunction with the sewing mechanism for simultaneous performance of the sewing and inseam trimming operations about the sole margin of the shoe.

The jacked shoe is guided and positioned with relation to the several operating devices during the transfer of the operation about the sole margin of the shoe by means of a channel guide 138 which is arranged to ride in a stitch receiving channel and to support the shoe against the needle, and a welt guide (not shown) which is arranged to engage yieldingly against and to be periodically locked against the outer edge of the shoe.

The sewing instrumentalities of the illustrated machine comprise the curved hook needle 120 which together with its supporting segment is carried on an oscillatory feed lever 140 having back and forth movement in the line of feed. The looper 122 and thread finger 124 are supported and arranged to cooperate with the curved hook needle 120 in such a manner as to substantially confine the movements of these elements, and the sewing thread to that side of the sewing point away from the rotary tubular trimming knife 130, and thus to make possible the placing of the sewing mechanism and the trimming mechanism of the machine in close relation to one another at the point of operation on the margin of the shoe sole. The looper 122 is supported on a rock shaft 142 to turn on a small radius on an axis inclined forwardly from the vertical and substantially in line with the end of the needle in the needle threading position. The looper acts to carry the thread forwardly around the hook of the needle to the left in a counter-clockwise direction, while at the same time the thread finger 124 engages a portion of the thread extending between the looper and the work, and moves substantially in the line of feed to the right away from the looper and needle and away from the completed stitches of the seam to assist in positioning the thread in the needle hook and to provide slack thread at the work side of the needle loop. As the needle is substantially withdrawn through the work and carries with it the needle loop, the thread finger again moves to the left to give up this excess thread.

As best shown in Fig. 3, the supporting rock shaft 142 for the looper 122 is supported for rotational movement in a bore in a forwardly extending bracket 144 carried on the nose of the sewing head. The rock shaft 142 is provided at its upper end with a bearing collar 146 which engages against the upper end of the bearing support and is provided adjacent its lower end with a worm gear 148 which meshes with a worm on a forwardly extending driving sleeve 150 which is externally supported on a bearing formed on the bracket 144. A tapered pinion 152 formed on the rearward end of the driving sleeve 150 meshes with a correspondingly tapered gear segment 154 on one arm of a bell-crank lever 156 supported

to turn on a sleeve element indicated at 158 in Fig. 3. The upwardly extending arm of the bell-crank 156 is connected by a link 160 with the downwardly extending arm of a looper cam lever 162.

The thread finger 124 is secured to the forward end of a drive shaft 164 which is mounted within the sleeve drive shaft 150. At its rear end the shaft 164 is formed with a bevelled gear segment 166 meshing with a bevelled gear segment 168 which constitutes one arm of the bell-crank 170 mounted to turn on the sleeve element 158, the other arm of which is connected by a link 172 with a downwardly extending arm of a thread finger cam lever 174.

The illustrated machine is provided with means similar to that illustrated in the copending application of Morrill above referred to, for gripping the thread upon the completion of the operation about the shoe. As shown in said application, the thread finger 124 is arranged upon the stopping of the sewing mechanism to be moved an abnormal distance to the right into engagement with a thread gripper arm 180 which is pivotally supported on the housing 144, and is yieldably supported in operating position by means of a spring wire 182 connected at its upper end to a stationary pin 184 and at its lower end to a slot 186 in the upper end of the gripper member 180.

In accordance with the invention, a novel and improved means is provided for controlling and for severing the thread, which is particularly adapted for use in a machine having the work guiding and sewing instrumentalities above described, and which is preferably provided with a tubular inseam trimming knife and with an automatic support or jack movable to transfer the operation of the sewing and trimming instrumentalities about the sole margin of the shoe.

In the illustrated form of the invention, the movement of the thread finger to the right into engagement with the cooperating gripper member to grip the thread is rendered operative also to position a portion of the thread leading from the work against a supporting surface formed on the channel guide, and a thread severing knife is then caused to move downwardly parallel to the channel guide to sever the thread. This movement of the knife is timed to take place while the thread is tautly held after the sewing mechanism has been brought to its stop position and before the shoe is further advanced to finish trim the inseam. As shown in the drawings, the channel guide 138 is formed with a rearwardly extending shouldered or notched portion 190 (see Figs. 2, 3 and 5) across which a portion of the thread extending from the work is drawn by the thread finger 124 during its movement to the abnormal thread gripping position of Figs. 3, 4 and 5. The thread thus supported against the notched portion 190 of the channel guide 138 is arranged to be severed by the operation of a knife blade 192 which is adjustably secured to the lower end of an arcuate knife carrier member 194. The blade 192 is arranged to move along one face of the channel guide and across the edge of the supporting surface provided by the notched portion 190 of the channel guide to sever the thread.

The arcuate support 194 is formed with a slot 200 to receive two stationary guide pins 202 and 204, and is formed at its under side with an arcuate tongue surface 206 which rides in a shallow groove 208 formed in the flat face of the sewing head bracket 144 toward the inseam trimming knife. The knife 192 and its operating arcuate

support 194 are shown in their fully advanced severing position in Figs. 3 and 4, in which the positioning pin 202 is engaged against the upper end of the slot 200 on the knife support or guide 194.

The arcuate support 194 and knife 192 are arranged to be actuated upon stopping the machine from connections controlled from the eccentric rock shaft 100 which are in part the same connections normally employed for actuating the welt severing knife designated at 210 in Fig. 2. The operating connections referred to, include a laterally extending arm (not specifically illustrated) on the shaft 100, a link 212 secured at its rear end to said arm, and at its forward end to a downwardly extending arm 216 carried on a transversely extending rock shaft 218 (see Fig. 2). These connections together with a cam-shaped arm 219 on the shaft 218 comprise the conventional connections for operating the welt severing knife 210. In the illustrated construction as best shown in Fig. 2, the lever arm 219 has pivotally connected thereto one end of a link 220, the other end of which is connected to the rearwardly extending arm of a lever 222 pivoted at 224 on the sewing head. A follower roller 226 mounted on the forwardly extending arm of the lever 222 is arranged for engagement in a cam slot 228 formed in an upwardly extending link 230 connected at its lower end to the cutter slide 194. That portion of the link 230 forming one side of the slot 228 is severed adjacent its upper end and is bent inwardly to form a spring detent adapted to support the actuating roller 226 yieldably in the upper end of the slot 228.

The operation of the thread controlling and severing devices to support and to sever the thread when the machine is stopped will be briefly described as follows: Upon the completion of the last stitch of the inseam, the machine is automatically stopped through the operation of the stop motion. The control shaft 74 is rocked to release the main driving clutch 46, 48 and to connect the lock bolt carrier mechanism 82 as indicated in Fig. 1 to put in operation the separately driven reverse sewing machine stop motion of the machine. In accordance with the usual practice, the sewing machine is stopped with the needle withdrawn from the work, and with the thread finger moved an abnormal distance to the right into engagement with the thread gripper member 138 as shown in Figs. 4 and 5, to grip the thread, this motion of the thread finger acting in accordance with the invention further to position a portion of the thread extending from the work across the notched surface 190 of the channel guide 138. The movement of the sewing machine stop motion, the lock bolt carrier 82 first to the right and then to the left is effective through link 83, bell-crank 90, link 92 and clutch lever 98 (see Figs. 1 and 2) to engage the auxiliary eccentric clutch to drive the eccentric through one revolution. Eccentric rock shaft 100 connected with eccentric strap 49 is rocked first in a clockwise direction as viewed from above, and finally in a return or counterclockwise direction. A first portion of the clockwise movement of the eccentric rock shaft 100 is rendered operative to operate the thread severing knife as the actuating lever 222 and roller 226 are yieldably engaged in the upper end of the slot 228, is rocked and moves the knife edge 192 downwardly in a shearing movement with relation to the channel guide 138 to sever the thread. During the continued move-

ment of the eccentric rock shaft 100 in the clockwise direction to impart an additional increment of feeding movement to the work, to finish-trim the inseam, to disengage the jacked shoe from the operating mechanism, and to complete the operation of the pattern mechanism so that the jack is returned to an initial loading position, the roller 226 is forced out of its position at the upper end of the slot 228 and rides downwardly in the slot 228.

It will be understood that the invention is not limited to the specific embodiment shown, and that various deviations may be made therefrom without departing from the spirit and scope of the appended claims.

What is claimed is:

1. In a shoe inseam sewing machine, sewing instrumentalities including a needle, a channel guide having formed thereon a supporting surface to be engaged by a portion of the thread extending from the work, and a thread cutter movable in cooperative relation to the channel guide to sever a portion of the thread engaged against said surface.

2. In a shoe inseam sewing machine, work guiding and sewing devices including a channel guide, a needle, a driving and stopping mechanism for the machine, means operative in stopping the machine for drawing a length of thread extending from the work across the channel guide, and a thread cutter movable in cooperative relation to the channel guide to sever the thread.

3. In a shoe inseam sewing machine, work guiding and severing devices including a channel

35 guide having formed thereon a thread engaging surface, a needle, a thread finger, a gripper device arranged to cooperate with the thread finger to grip the thread and to position a portion of the thread extending from the work across said surface, and a thread severing knife movable to sever a portion of the thread against the support provided by said surface.

4. In a shoe inseam sewing machine, work guiding and sewing devices including a curved hook needle, a looper, a thread finger, a channel guide having formed thereon a thread engaging surface, and a thread cutting knife supported against the channel guide for movement across said surface to sever the thread.

5. In a shoe sewing machine, shoe guiding and sewing devices including a channel guide, a curved hook needle, a looper, a thread finger arranged to draw a portion of the thread extending from the work substantially in the direction of the line of feed away from the needle and across the channel guide, and a thread cutting knife movable in cooperative relation to the channel guide to sever said portion of the thread.

6. In a shoe sewing machine, a curved hook needle, a looper, a thread finger arranged to draw thread substantially in the direction of the line of feed away from the needle, a channel guide having formed thereon a thread supporting surface adapted to be engaged by a portion of the thread drawn out by the thread finger, a thread cutter supported in sliding engagement with the channel guide for movement across said surface, and means for moving the thread cutter to sever the thread.

7. In a shoe sewing machine, a curved hook needle, a looper, a thread finger arranged to draw thread substantially in the direction of the line of feed away from the needle, a channel guide having a thread engaging surface past which the thread is drawn by the thread finger, a thread

cutter arranged for cooperative movement with relation to the channel guide to sever a portion of the thread supported against said surface, a driving and stopping mechanism for the machine, and means operative in stopping the machine for actuating the thread cutter to sever the thread.

8. In an inseam shoe sewing machine, a curved hook needle arranged to enter the welt side of the work and to emerge in the stitch receiving channel, a looper, a thread finger arranged to draw thread in the line of feed away from the completed stitches of the seam, a channel guide having a thread engaging surface, a gripper device operative upon stopping the machine to cooperate with the thread finger to grip the thread and to position a portion of the thread extending from the work across said surface, and a thread cutter movable to sever a portion of the thread against the support provided by said surface.

9. In a shoe sewing machine, a curved hook needle, a looper, a thread finger arranged to draw thread substantially in the direction of the line of feed away from the needle, a channel guide having a thread engaging surface past which the thread is drawn by the thread finger, driving and stopping mechanism for the machine, a gripper device arranged for cooperative engagement with the thread finger upon stopping the machine to grip the thread, a thread cutting knife supported against the channel guide for shearing movement past said surface to sever the thread, and means operative in stopping the machine to actuate the thread cutter.

10. In a shoe sewing machine, shoe operating devices including a rotary tubular inseam trimming cutter arranged to trim a portion of the inseam held together by the last completed stitches of the seam, an inseam sewing mechanism comprising a curved hook needle, a looper, a thread finger movable in a direction substantially in the line of feed and away from the completed stitches of the seam, a channel guide for guiding the shoe with relation to the trimming cutter and inseam sewing mechanism and having a thread engaging surface disposed at that side of the needle away from the completed stitches of the seam, a thread gripping device arranged to cooperate with the thread finger when the sewing mechanism is stopped to grip the thread and to position a portion of the thread extending from the work tautly across said surface, a thread severing knife supported against the channel guide for movement across said surface to sever the thread, and means for actuating the knife.

11. In a shoe machine, an automatic shoe support, an inseam trimming cutter arranged to trim a portion of the inseam held together by the last completed stitches of the seam, an inseam sew-

ing mechanism comprising a curved hook needle, a looper, a thread finger movable in a direction substantially in the line of feed and away from the completed stitches of the seam, a channel guide for guiding the shoe with relation to the trimming cutter and inseam sewing mechanism and having a thread engaging surface, a thread gripper device operative upon stopping the sewing mechanism to cooperate with the thread

- 5 finger to grip the thread and to position a portion of the thread extending from the work tautly across said surface, a thread cutter movable with relation to the channel guide to sever a portion of the thread against the support provided by said surface, and a driving and stopping mechanism for the machine including clutching devices operative to stop the machine including the sewing mechanism and automatic support, and an auxiliary mechanism including connections acting when the machine is stopped to actuate the thread cutter, and thereafter to further feed the shoe to finish-trim the inseam.

- 10 12. In a shoe machine, an automatic shoe support, an inseam trimming cutter arranged to trim a portion of the inseam held together by the last completed stitches of the seam, an inseam sewing mechanism comprising a curved hook needle, a looper, a thread finger movable in a direction substantially in the line of feed and away from the completed stitches of the seam, a channel guide for guiding the shoe with relation to the trimming cutter and inseam sewing mechanism and having a thread engaging surface, a thread gripper device operative upon stopping the sewing mechanism to cooperate with the thread finger to grip the thread and to position a portion of the thread extending from the work tautly across said surface, a thread cutter movable with relation to the channel guide to sever a portion of the thread against the support provided by said surface, and a driving and stopping mechanism for the machine operative to stop the sewing mechanism and to grip the thread, to actuate the thread cutter to sever the thread, and thereafter to further move the shoe to finish-trim the inseam, and to disengage the shoe from the channel guide.

15 RUTH W. MORRILL,
Administratrix of the Estate of Alfred R. Morrill,
Deceased.
